UNITED STATES PATENT OFFICE.

ABRAM B. TILTON, OF BAYHEAD, NEW JERSEY.

WASTE AND OVERFLOW CONNECTION FOR BATH-TUBS, WASHBASINS, &c.

1,101,974.

Specification of Letters Patent. Patented June 30, 1914.

Application filed October 28, 1913. Serial No. 797,837.

To all whom it may concern:

Be it known that I, ABRAM B. TILTON, a citizen of the United States, residing at Bayhead, in the county of Ocean and State of New Jersey, have invented new and useful Improvements in Waste and Overflow Connections for Bath-Tubs, Wash-basins, &c., of which the following is a specification.

10 This invention relates to waste and overflow connections for bath tubs, wash basins, etc., the object of the invention being to provide a device of this character which is simple of construction reliable and efficient 15 in action and controls both the discharge of water from the bowl and the outlet of the overflow water.

20 The invention consists of the features of construction, combination and arrangement of parts herein fully described and claimed, reference being had to the accompanying drawing, in which:—

25 Figure 1 is a vertical sectional view showing the application of the invention to a wash basin. Fig. 2 is a sectional plan view on the line 2—2 of Fig. 1. Fig. 3 is a sectional plan view on the line 3—3 of Fig. 1.

30 Referring to the drawing, 1 designates a wash bowl, having the usual rearwardly extending ledge or shelf 2 and waste outlet 3.

35 My improved combined waste and overflow connection or attachment comprises a discharge pipe or casing 3^a, which is designed to be arranged beneath the shelf 2 and is provided at its top with a flange 4 for attachment to the shelf in any suitable manner, the said casing being provided at 40 its lower end with a discharge port 5 for connection with the usual waste pipe 6. The casing is formed at a suitable elevation with an inlet 7 connected in practice by an elbow or other suitable fitting 8 with the outlet 3 of the bowl 1, whereby the water from the bowl is conducted into the casing for discharge.

45 A combined over-flow and discharge tube 9 extends vertically within the casing and 50 communicates at its lower end with the discharge port 5. The said lower end of the tube 9 is snugly fit within the port 5, and is thereby supported in position, and the upper end of the tube, which is normally 55 open, terminates adjacent to a cross piece 10 suitably secured at the top of the casing.

The upper end of the tube 9 terminates at and determines the maximum level of the water in the bowl 1, and the casing 3 is normally in communication with the bowl, 60 so that the water in the bowl and casing will stand at the level. If such maximum level should be exceeded, it will of course be understood that the waste or over-flow water will discharge through the tube 9 and 65 be carried off through the pipe 6.

The lower end of the tube 9 is provided with an inlet opening 11, and formed upon said tube and communicating with said opening is a segmental chamber 12, open at 70 one end and extending partially around the tube, the said open end of the chamber being provided with a valve seat 13.

Journalized at its lower end in the bottom of the casing and at its upper end in the 75 cross bar 10 is a rock shaft or stem 14 provided at its lower end with a lateral arm or offset 15 carrying a valve 16 to engage the seat 13. The upper end of the stem projects through and above the top 80 of the ledge 2 of the bowl and is provided with a hand wheel or manipulating device 17, whereby the shaft or stem 14 may be rocked or oscillated to move the valve 16 into and out of engagement with the seat 13. 85 In practice the handle 17 may be disposed between the usual hot and cold water faucets, and in applying the invention to a bath tub the parts will be arranged as required or circumstances demand. 90

It will be evident from the foregoing description that by adjusting the valve 16 to closed position the flow of water from the bowl may be cut off, allowing any amount of water to be retained in the bowl until 95 the maximum level is exceeded, the over-flow water passing from the casing into the top of the tube 9 and thence passing downward through the tube to the waste pipe 6. When the valve 16 is opened the waste water 100 contained in the bowl will discharge directly from the bowl into the casing and thence through the chamber 12 and port 11 into the tube 9 and finally through the pipe 6. 105

It will thus be seen that my invention provides a simple, reliable and efficient combined over-flow and waste connection or attachment for wash basins, bath tubs and the like, which can be readily applied in 110 position and which is adapted to serve its intended functions in a highly satisfactory

manner. While the structure shown is preferred, it will of course be understood that modifications within the scope of the appended claims may be made without departing from the spirit or sacrificing any of the advantages of the invention.

I claim:

1. A waste and over-flow connection or attachment for wash basins, bath tubs and the like comprising a casing having a water inlet at one side and a water discharge port in its bottom, an over-flow tube disposed in said casing in spaced relation thereto, said tube communicating at its lower end with the water discharge port and open at its upper end for the admission of the waste water thereto, the lower end of said tube being provided with a waste port extending partially around the same and provided with a valve seat, a rock shaft journaled in the casing exteriorly of said tube and having a lateral projection provided with a valve for engagement with said seat, and means for rocking said shaft.
2. A combined waste and over-flow connection or attachment for wash basins, bath

tubs and the like comprising a casing having a water inlet at one side and a water discharge port in its bottom, an over-flow tube extending vertically within said casing and communicating at its lower end with said water discharge port, said tube having its upper end open for the flow of water thereto and being provided adjacent its lower end with a segmentally curved water inlet port extending partially around its circumference and terminating in a valve seat, a rock shaft extending vertically within the casing exteriorly of said tube, an arm projecting laterally from said shaft for movement toward and from said valve seat, a valve carried by the arm to engage the valve seat, and means upon the upper end of the shaft for imparting a rocking motion thereto.

In testimony whereof I affix my signature in presence of two witnesses.

ABRAM B. TILTON.
